(57) **CLAIM**

We claim the ornamental design for a decompression panel, as shown and described.

DESCRIPTION

FIG. 1 is a front perspective view of a decompression panel showing our new design in an aircraft assembly environment;

FIG. 2 is an enlarged front perspective view of the decompression panel design shown in FIG. 1;

FIG. 3 is a rear perspective view of the decompression panel design shown in FIG. 2;

FIG. 4 is a front plane view of the decompression panel design shown in FIG. 2;

FIG. 5 is a rear plane view of the decompression panel design shown in FIG. 2;

FIG. 6 is a left side view of the decompression panel design shown in FIG. 2; and,

FIG. 7 is a right side view of the decompression panel design shown in FIG. 2.

Top and bottom views of the decompression panel design include no surface ornamentation and are therefore omitted.
